DESIGN FOR A BUILDING

Ernest J. B. La Lumière, Providence, R. I.

Application November 29, 1937, Serial No. 73,233

Term of patent 14 years

To all whom it may concern:

Be it known that I, Ernest J. B. La Lumière, a citizen of the United States, residing at Providence, in the county of Providence and State of Rhode Island, have invented a new, original, and ornamental Design for a Building, of which the following is a specification, reference being had to the accompanying drawing, forming part thereof.

In the drawing:

Fig. 1 is a front elevational view of a building showing my new design; and

Fig. 2 is a top plan view thereof.

I claim:

The ornamental design for a building as shown.

ERNEST J. B. LA LUMIÈRE.
